UNITED STATES PATENT OFFICE

2,009,089

INDICATING PLUG FUSE

Frank C. La Mar, New York, N. Y.

Application January 11, 1934, Serial No. 706,171

6 Claims. (CL 200—121)

This invention relates to electrical devices, particularly to thermal fuses for use in connection with electrical circuits, and more especially to what is known as a plug fuse, combined with means for indicating the integrity of the fusible element.

It is quite universally known that it is necessary to protect electrical circuits by means of devices, such as thermal fuses, which melt or become disintegrated or destroyed when an excessive flow of current passes through the circuit of which the fuse forms a part. An especially well known form of thermal fuse is that known as a "plug fuse". Ordinary plug fuses consist, generally, of an insulating body having two terminals on the outside thereof, so constructed and arranged as to be readily brought in contact with the terminals of an electrical circuit, by way of what is known usually as a fuse block. These fuses are universally used; are made by many different manufacturers; and must all be usable in practically any of the well known forms of fuse blocks; so that they have become, in truth, standard, and may well be referred to as, standard fuse plugs. At any rate they are substantially standard as regards their general external dimensions.

Various forms of plug fuses have been made, especially for the purpose of enabling one to quickly discern whether or not the fusible or thermal element is intact. It is quite the universal impression that success has not been fully attained in regard to the feature of indicating the integrity of the fusible element.

A principal object of applicant's invention is to provide a device, which may well be called a combined fuse and fuse integrity indicating device. In providing such a device, applicant has had in mind that it preferably should be in external dimensions substantially the size of the standard plug fuse, so that it may be used with a facility equal to that of a plug fuse in those situations where a plug fuse is now used.

A further object which applicant has in mind in producing his combined fuse and fuse integrity indicator is that the cost must be reduced to a point where, if possible, it approximates the present cost of ordinary plug fuses. To this end, applicant has, as a further object of his invention, the production of a device in two parts, separable one from the other, one part supporting and protecting the thermal element, which part is removable, and the other part performing the indicating functions desired by applicant,

and combinable with the first part to make a complete indicating fuse part.

A further object of applicant's invention is to produce a combined fuse and fuse integrity indicator which will have substantially the same external dimensions as a standard plug fuse.

Other objects and advantages will appear as the description of the particular physical embodiments selected to illustrate the invention progresses, and the novel features will be particularly pointed out in the appended claims.

In describing the invention in detail and the particular physical embodiments selected to illustrate the invention, reference will be had to the accompanying drawing and the several views 15 thereon, in which like characters of reference designate like parts throughout the several views, and in which:

Figure 1 is a cross-sectional view of a plug fuse embodying applicant's invention; Fig. 2 is a top plan view of the device as shown by Fig. 1; Fig. 3 is a cross-sectional view of the device as shown by Fig. 1 on the plane indicated by the line III—III viewed in the direction of the arrows at the ends of the line; Fig. 4 is a cross-sectional view of the device as shown by Fig. 1 on the plane indicated by the line IV—IV of Fig. 1, viewed in the direction of the arrows at the ends of the line; Fig. 5 is an elevational view of the indicator portion of applicant's combined fuse and fuse integrity indicator, with some parts broken away to more clearly show the construction.

Figure 1, broadly considered, shows a combined plug fuse and fuse integrity indicator having as essential parts the usual end contact terminal 1; the screw threaded shell terminal 2; and a thermal fusible element 3 connecting terminal 1 and screw thread shell 2. These parts are comparable with and constitute the principal parts of the usual and ordinary fusible plug. In addition to the plug portion there is an indicator portion which broadly includes a gaseous discharge lamp 4, preferably of the neon filled type, having one terminal 5 connected to the contact terminal 1 and the other terminal connected, through a high ohmic resistance 6, to an electrical conducting rod 7 electrically connecting to screw shell 2. A construction such as has been described serves all of the functions of the ordinary plug fuse and in addition operates to indicate the integrity of the fusible element 3 because when that element is intact the lamp 4 is not illuminated, but when the thermal element 3 is destroyed then the lamp 4 is illuminated indicating the destruction of the fusible element 3.

Applicant's construction preferably embodies a body of insulating material 8 substantially in the form of a hollow cylinder. The hollow cylinder is closed at one end by the insulating body 9 substantially in the form of a disc.

The body 8 is formed with projections 10 forming a screw thread which cooperates with the screw threaded metallic shell 2 in that the screw threaded shell 2 may be screwed onto the body 8 and thereby be retained in place.

The screw thread shell 2 has inturned ends 11 and 12 which cooperate with the disc 9 to retain it in place.

In order to separate the lamp 4 from the interior of the fuse plug within which the fusible element 3 is positioned, applicant provides an interior cylindrical tube 13 which has an internal diameter corresponding with the diameter of the upper opening 14 of the body 8 and has an external diameter such that it just fits within the bore 15 which is slightly larger than the opening 14 of the body 8.

Applicant provides a closure for the lower end of the cylinder tube 13 by placing a metallic cap 16 thereover which fits tightly against the wall of the cylindrical tube and is preferably provided with a depending bulge 17 for a purpose to be hereinafter described.

Applicant provides an indicating lamp carrier 30 designated as a whole by C. This carrier is preferably formed in two parts 18 and 19 divided along the plane indicated by line 20 and each being for a greater portion of its length substantially the half of a hollow cylinder so that applicant calls the members hollow semi-cylindrical.

Each of the members 18 and 19 has outstanding arms at its upper portion, that attached to 18 being designated 21 and that attached to 19 being designated 22. The arms 21 and 22 rest one with 40 the other so that the top surface of 21 is one continuous unbroken line and the bottom surface of the two is one continuous unbroken line.

In order to hold the hollow semi-cylindrical members together, applicant prefers to use a metallic band 23 at the upper portion, which although, perhaps not absolutely necessary, is desirable, and a metallic cap 24 at the lower portion. This metallic cap 24 fits tightly around the inter-fitted hollow semi-cylindrical members and is 50 provided with an orifice 25 for the passage therethrough of one lead 5 of the lamp 4.

The lead 26 of the lamp 4 is preferably carried up and alongside of the lamp 4 and then connected to one terminal of the resistance 6. This 55 resistance 6 is of the grid leak type and where applicant's device is to be used on 110 volt circuits is of the order of about 50,000 ohms resistance. The other terminal of the resistance 6 is connected by the conductor 27 to the metallic rod 7.

Metallic rod 7 is positioned, preferably, by moulding in the arm 22 of the hollow semi-cylinder member 19 and is positioned to pass down through a bore 27' formed in the body 8 so that its lower preferably scarfed or pointed end 28 may 65 contact with the metallic screw threaded shell 2.

The assembly of the device is accomplished by first soldering one end of the fusible member 3 in the terminal 1 and at the same time soldering the bulge 17 of the metallic cap 16 of the cylindrical tube 13 to the same terminal. The disc 9 carrying with it the associated parts is then put in place, as shown by Fig. 1, with one end of the fusible link 3 passing through an orifice 29 and positioned to contact with screw threaded shell 75 2, and the upper end of the cylindrical tube 13

seating in the bore 15, whereupon the screw thread shell 2 is screwed onto the body 8 and holds all parts in proper position.

In order to assemble the indicator carrier C the lamp 4 has one terminal thereof, 5, passed through the orifice 25 in the cap 24 and a drop of solder applied, then the other terminal is connected to a resistance 6 which in turn is connected to rod 7, after which the two portions of the carrier are placed together as shown in Fig. 1 with the band 23 slipped up over them and the cap 24 placed over their lower ends, the resistance 6 resting in a cavity 31 formed therefor.

The carrier C is positioned by inserting it in the orifice 14 while the rod 7 is inserted in the bore 27' after which it is forced home, as shown by Fig. 1, with the small drop of solder 30 resting in the bulge 17 of the metallic cap 16 and the rod 7 contacting with screw threaded shell 2.

If the fusible link 3 becomes destroyed, the carrier C is withdrawn and inserted in another fuse plug formed exactly as is the body 8 with its associated parts.

Although I have particularly described one particular physical embodiment of my invention and explained the operation, construction and principle thereof, nevertheless, I desire to have it understood that the form selected is merely illustrative, but does not exhaust the possible physical embodiments of the idea of means underlying my invention.

What I claim as new and desire to secure by Letters Patent of the United States, is:

1. A plug fuse having in combination: an outer cylindrical screw threaded metallic shell contact; a metallic contact positioned axially of the shell; a thermal element connecting the contacts; a lamp having two terminals; means supporting and enclosing the lamp and positioning the lamp with its longitudinal axis axially of the metallic shell, said means removable bodily and including means for forming electrical connections to the contacts, said last mentioned means including a rod carried by the lamp supporting means position to make contact with the screw threaded metallic shell.

2. As the plug fuse element of a combined plug fuse and fuse integrity indicator, in combination: a hollow insulating body formed with a screw thread upon a portion of its outer periphery; an insulating disc carrying a centrally disposed metallic contact closing one end of the hollow body; a cylindrical tube within the hollow body, one end of the tube fitting within a bore of the hollow body of greater diameter than the end opening of the hollow body, the other end of the cylindrical tube being provided with a metallic cap embracing a portion of the outer surface of the cylindrical tube and being soldered together with one end of a fusible element to the centrally disposed contact of the disc, the other end of the fusible element being carried through an orifice in the body and positioned against the outside periphery of the body; and a screw threaded shell adapted to cooperate with the screw threads of the body and provided with means for holding the disc in place.

3. As a plug portion of a combined fusible plug and indicator, the combination of a hollow substantially cylindrical body provided with an internal wall supporting and defining, from the remainder of the space within the hollow body, a space communicating with one open end of the hollow body; a fusible link positioned within the said remaining space; means for closing the other open

end of the cylindrical body, a substantially central metallic terminal carried by the said means for closing; a metallic shell surrounding a portion of the outside of the hollow body; and a fusible link connecting the shell and the metallic terminal.

4. As an indicator lamp carrier of a combined fuse and fuse integrity indicator, in combination: two substantially semi-cylindrical members; means for holding said members together to substantially form a tube closed at one end; each of said members bearing an arm interfitting with an arm of the other member; a metallic rod attached to one of said arms and depending therefrom so positioned that when the combined semi-cylindrical portions are positioned centrally of a plug fuse the depending arm will be positioned to pass through a bore of the plug fuse and contact the ordinary screw shell on the outer periphery thereof; and an indicator lamp having a resistance in series therewith connected between the said rod and the metallic holding means closing one end of the assembled semi-cylindrical members.

5. An indicating plug fuse of substantially standard contour and over-all dimensions, having in combination; a hollow body of insulating material; an outer cylindrical threaded metallic shell contact; an exterior metallic contact positioned axially of the body, and having a contact portion extending within said body; a thermal ele-

ment connecting the contacts; a fuse integrity indicating lamp including an evacuated shell having two terminals; and means supporting and enclosing the lamp and provided with contacts for engagement with portions of said plug contacts when said lamp and its supporting means are assembled with said plug; said lamp contacts including means positioned to make contact with the interior of the screw threaded metallic contact.

6. An indicating plug fuse of substantially standard contour and over-all dimensions, having in combination; a hollow body of insulating material; an outer cylindrical threaded metallic shell contact; an exterior metallic contact positioned axially of the body, and having a contact portion extending within said body; a thermal element connecting the contacts; and having its most readily fusible portion confined within said hollow body; a fuse-integrity-indicating lamp having two terminals; and means supporting and enclosing the lamp and provided with contacts for engagement with portions of said plug contacts when said lamp and its supporting means are assembled with said plug; said lamp contacts including a rod positioned to make contact with the interior of the screw threaded metallic contact, said lamp-support, lamp and lamp contacts being removable bodily from said plug, by a right line movement of said lamp support.
